United States Patent Office.

JAFEW S. VAN BUREN, OF GREEN ISLAND, NEW YORK.

Letters Patent No. 101,683, dated April 5, 1870.

IMPROVEMENT IN HOT-AIR FURNACES.

The Schedule referred to in these Letters Patent and making part of the same.

To all whom it may concern:

Be it known that I, JAFEW S. VAN BUREN, of Green Island, in the county of Albany and State of New York, have invented a new and valuable Improvement in "Hot-Air Furnaces," and I do hereby declare that the following is a full, clear, and exact description of the construction and operation of the same, reference being had to the annexed drawings making a part of this specification, and to the letters and figures of reference marked thereon.

Figure 1, of the drawings, is a side view of my invention.

Figure 2 is a central vertical longitudinal section of the same.

Figure 3 is a perspective view of the feeder.

Figure 4 represents a top view of the distributing-plate in the hot-air chamber.

My invention relates to heaters, and consists in the construction and novel arrangement of devices designed to constitute an improved hot-air furnace, which shall be safe, although resting upon a wooden floor, shall consume the gases generated near the feeder or fuel-opening, and shall otherwise prevent them from issuing thereout at any time.

The letter A of the drawings designates a shallow metal pan designed to hold an inch or so of water, and thus to serve as an efficient non-conductor between the furnace and the floor.

B represents the feeder or fuel-opening, provided with a flue or flues, c, in its floor or base, whereby oxygen is supplied through the perforations in the end, for the consumption of the gases immediately about the opening.

In order to prevent the escape of these gases when the door of the furnace is open, for the introduction of fuel or other purpose, the pendent gate d is arranged across the throat of the feeder.

E designates the hot-air chamber. It is in the form of a hollow frustum of a cone, inverted within the upper portion of the furnace, and provided with an upright cone in the center.

The cold air is admitted by the flues e e from the rear of the furnace, and is kept in contact with the heated walls of the inverted frustum and central cone by means of the circular distributing-plate G within the hot-air chamber.

An opening is made in the front portion of the plate G to allow the heated air to escape from the lower portion of the hot-air chamber E.

What I claim as my invention, and desire to secure by Letters Patent, is—

1. The feeding-throat B, provided with the base flues c, when constructed as and for the purposes specified.

2. The W-shaped hot-air chamber E, provided with distributing-plate G, and having rear cold-air entrance-flues e e as specified.

In testimony that I claim the above, I have hereunto subscribed my name in the presence of two witnesses.

J. S. VAN BUREN.
